Specification for Design.

Patented Mar. 2, 1920.

Application filed October 21, 1919. Serial No. 332,313. Term of patent 14 years.

To all whom it may concern:

Be it known that I, CLEMENT E. ECKRODE, a citizen of the United States, residing at Newark, county of Essex, and State of New Jersey, have invented a new, original, and ornamental Design for Treads for Tires, of which the following is a specification, reference being had to the accompanying drawing, forming part thereof.

Figure 1 is a face view showing my new and ornamental design for a tire tread, and Fig. 2 is a section taken on line 2—2 in Fig. 1.

I claim:

The ornamental design for a tire tread, as shown.

CLEMENT E. ECKRODE.
